US00D537086S

(12) **United States Design Patent** (10) Patent No.: **US D537,086 S**
(45) Date of Patent: **** Feb. 20, 2007**

(54) **ICON FOR A PORTION OF A DISPLAY SCREEN**

(75) Inventors: **Shelley Armstrong**, Redmond, WA (US); **Corey Marion**, Colfax, NC (US); **David Lanham**, Greensboro, NC (US); **Travis Zuker**, Randleman, NC (US); **Nino Yuniardi**, Seattle, WA (US)

(73) Assignee: **Microsoft Corporation**, Redmond, WA (US)

(**) Term: **14 Years**

(21) Appl. No.: **29/229,692**

(22) Filed: **May 11, 2005**

(51) **LOC (8) Cl. 14-04**

(52) **U.S. Cl. D14/489**

(58) **Field of Classification Search** D14/485-95; D18/24-33; D19/6; D20/11; D21/324-33; 715/700-866

(57) **CLAIM**

The ornamental design for an icon for a portion of a display screen, as shown and described.

DESCRIPTION

The FIGURE is a front view of an icon for a portion of a display screen showing our new design.

The broken line showing of the portion of a display screen is for illustrative purposes only and forms no part of the claimed design.

1 Claim, 1 Drawing Sheet

The Figure

UNITED STATES PATENT AND TRADEMARK OFFICE
CERTIFICATE OF CORRECTION

PATENT NO. : Des. 537,086 S
APPLICATION NO. : 29/229692
DATED : February 20, 2007
INVENTOR(S) : Armstrong et al.

Page 1 of 3

It is certified that error appears in the above-identified patent and that said Letters Patent is hereby corrected as shown below:

Drawings

The title page showing an illustrative figure should be deleted and substitute therefore the attached title page consisting the Figure.

The drawing sheets consisting of figure should be deleted and substitute therefore the attached drawing sheets consisting of the figure.

Signed and Sealed this

First Day of May, 2007

A handwritten signature in black ink, appearing to read "Jon W. Dudas". The signature is written in a cursive style with a large, stylized "J" and "W".

JON W. DUDAS
Director of the United States Patent and Trademark Office
